(57) **CLAIM**

The ornamental design for an infusion solution bag, as shown and described.

DESCRIPTION

FIG. 1 is a perspective view of the design according to the invention.

FIG. 2 is a front elevation view thereof, the rear view being a mirror image thereof;

FIG. 3 is a left side elevation view thereof, the right side being a mirror image thereof;

FIG. 4 is a top plan view thereof;

FIG. 5 is a bottom plan view thereof;

FIG. 6 is a cross-section thereof taken along line 6—6 as shown in FIG. 2;

FIG. 7 is an enlarged view of the cross-section as shown in FIG. 6, embraced by brackets 7—7; and,

FIG. 8 is a cross-section of the design taken along line 8—8 as shown in FIG. 2.
